UNITED STATES PATENT OFFICE.

ALBERT J. LOEPSINGER, OF PROVIDENCE, RHODE ISLAND, ASSIGNOR TO GENERAL FIRE EXTINGUISHER COMPANY, OF NEW YORK, N. Y., A CORPORATION OF NEW YORK.

METHOD OF SEALING GLASS BULBS.

1,241,229.

Specification of Letters Patent. Patented Sept. 25, 1917.

Original application filed July 3, 1912, Serial No. 707,472. Divided and this application filed March 11, 1916. Serial No. 33,632.

To all whom it may concern:

Be it known that I, ALBERT J. LOEPSINGER, of the city and county of Providence and State of Rhode Island, have invented a certain new and useful Method of Sealing Glass Bulbs; and I do hereby declare the following specification, taken in connection with the accompanying drawings, forming a part of the same, to be a full, clear, and exact description thereof.

The present application is a division of my application, Serial Number 707,472, filed July 3rd, 1912, Patent No. 1,199,090, Sept. 26, 1916. In that application there is set forth a method of preparing glass bulbs or similar frangible vessels for use in automatic sprinklers of that type which embodies in its construction a frangible vessel having expansible contents, and which is caused to be opened by the expansive or explosive force of the contents of such frangible vessel induced by the action of heat.

The method described in said application involves filling the bulb with a gas solution at normal temperature, then placing the bulb in a closed receptacle, then introducing pressure into said receptacle and there heating the bulb and its contents up to a desired high temperature, thereby permanently expelling a quantity of the liquid from the bulb, then cooling the bulb and its contents, and then sealing said bulb.

The present invention relates to the sealing of bulbs which thus contain a gas in solution, and the invention consists in a novel method of sealing such bulbs, which method is illustrated in the accompanying drawings and will be described in connection therewith.

Referring to the drawings, Figure 1 is a sectional view showing a bulb containing a gas solution and ready for sealing, and Fig. 2 is a side view partly in section of an apparatus which may be employed in carrying out the method of sealing the bulbs:

The frangible vessel comprises a bulb 1 of glass or similar material provided with an elongated hollow neck 2. It is understood that this bulb is filled with a gas solution up to the dotted line 3-3 and is ready to be sealed.

The method of sealing the bulb consists in placing the bulb with the gas solution therein in a closed receptacle and there seal-

ing the bulb under pressure so as to prevent the escape of gas from the gas solution.

The method of sealing the bulbs may be conveniently described in connection with the apparatus shown in Fig. 2, which is a suitable apparatus for carrying out the method.

Said apparatus comprises a receptacle 4 having an opening in its upper wall through which the bulb may be placed in position within the receptacle. The opening referred to its tightly closed by a cover 5, which is held securely in place by a screw 6 working in a bracket 7 rigidly secured to the body of the receptacle. The suitably shaped holding devices 8-8 are provided within the receptacle to receive and hold the bulb during the process of sealing. Communicating with the interior of the receptacle is a pipe 9 leading from a pump or compressed air reservoir (not shown), whereby the interior of the receptacle may be filled with air under pressure. The pipe 9 is provided with a valve 10 for controlling the admission of air to the receptacle. 11 is a relief valve which is to be set or adjusted at the pressure desired to be maintained within the receptacle and to prevent any greater pressure therein.

12 is a burner secured to the end of the pipe 13. The pipe 13 extends through the end wall of the receptacle and through a stuffing-box 14, and so that said pipe and the burner 12 carried thereby may be moved toward and from the bulb to be sealed when the same is in position within the receptacle. The outer end of the pipe 13 is connected by a link 15 to one end of a lever 16 pivoted at 17 to the bracket 18 secured to the wall of the receptacle. Preferably the bracket is provided with projecting lugs 19 and 20 adapted to be engaged by the bosses 21-22 respectively formed on the lever 16 to level the inward and outward movement of the burner 12.

Communicating with the pipe 13 outside of the receptacle is a pipe 23 leading to a supply of compressed air, and communicating with said pipe 23 is a pipe 24 leading to a gas supply, whereby a mixture of gas and air is supplied to the pipe 13. The valve 25 in the pipe 23 controls the admission of the mixture of gas and air to the pipe 13 and the burner 12. The pipes 23 and 24 are to

be connected with flexible pipes (not shown) in order to permit the to and fro movements of the pipe 13 and the burner 12.

The operation of the apparatus above described will be readily understood. Assuming the burner 12 to be lighted and to be in its outer or withdrawn position, the cover of the receptacle is removed and the bulb to be sealed is placed in the holding devices 8, the arrangement of said devices being such that the end of the neck of the bulb will be held substantially in line with the burner 12. The cover 5 is then secured in place and the valve 10 is opened to admit compressed air into the receptacle, preferably up to the pressure determined by the relief valve 11. The lever 16 is then moved to bring the boss 21 thereon into engagement with the lug 19, thereby moving the burner 12 toward the neck of the bulb and into the position shown in Fig. 2, thereby bringing the frame into position to impinge upon the end of the neck of the bulb, which, by the action of the heat, will be fused and closed and the bulb thereby hermetically sealed. The air-pressure within the receptacle will prevent any material escape of gas during the process of sealing.

Preferably an opening 26 is provided in one of the side walls of the receptacle in line with the bulb, with a pane of glass 27 in said opening through which the operator may note the progress of the fusing and observe when the bulb has been properly

sealed. The lever 16 is then moved to withdraw the burner, the amount of such movement being determined by the engagement of the boss 22 with the lug 20. The cover is then taken off, the bulb removed from the receptacle, another put in its place, and the operation as above described repeated. The receptacle 4 may be of any desired size to receive any desired number of bulbs, all of which bulbs may be sealed simultaneously, a separate burner being preferably provided for each bulb to be sealed.

I make no claim herein to the apparatus shown and described for use in connection with the sealing of the bulbs, which apparatus forms the subject of my application Serial No. 707,473, renewal Number 159,327, Apr. 2, 1917.

What I claim as my invention and desire to secure by Letters Patent is:

1. The method of sealing glass bulbs containing a gas in solution which consists in placing the bulb in a closed receptacle and there sealing the bulb under pressure.

2. The method of sealing a glass bulb provided with an elongated neck and containing a gas in solution which consists in placing the bulb in a closed receptacle and there fusing the end of the neck under pressure.

ALBERT J. LOEPSINGER.
